UNITED STATES PATENT OFFICE.

MAX KLAUSCH OF CHICAGO, ILLINOIS.

DRAPERY-SUPPORT.

1,253,693.

Specification of Letters Patent.

Patented Jan. 15, 1918.

Application filed March 29, 1917. Serial No. 158,172.

To all whom it may concern:

Be it known that I, MAX KLAUSCH, a citizen of the German Empire, residing at the city of Chicago, in the county of Cook and State of Illinois, have invented certain new and useful Improvements in Drapery-Supports, of which the following is a specification.

My invention relates to rods or poles which are used for the suspension of window curtains and other draperies, particularly those which are used in pairs and attached to rods or poles by rings slideable thereon. Where a single pole or rod is used for such suspension the proximate edges are not readily closed together. There is always a tendency to gape open and this is especially true where traverse cords are used, as the unavoidable stretching of the cords causes 20 a failure of the two curtains to close fully on each other.

It is the object of my invention to provide a curtain rod or pole on which a plurality of curtains may be so suspended that the proximate edges will overlap when they are moved together so that the window opening will be completely closed. It is so arranged that any stretching in the traverse cords will be compensated for, and the device therefor is simple, cheap and inexpensive. It is applicable to a great range of use without special construction, and it provides means for using stock rod material with the least possible amount of waste.

The principles of my invention are illustrated in the drawings, in which—

Figure 1 shows a front view of my improved curtain support;

Fig. 2 is an alternative construction;

Fig. 3 is a top view thereof;

Fig. 4 is an enlarged bottom view of a connecting or central member.

Further describing my invention with reference to the drawings: 1 represents the top board of a window casing, to which at one end are attached brackets 2 of the usual type for receiving and supporting one end of a curtain rod. The bracket 3 at the other end may be extended somewhat farther from the point of attachment for a purpose to be hereafter explained, but is also provided with a socket in the usual manner to receive the end of a curtain rod.

The rods upon which the draperies are suspended may be of the usual material, as of brass or coppered iron wire or rods, which

are centrally bent and recurved to form a central suspension member 4, and a plurality of outer members 5 and 6 spaced from each other and from the central member and extended longitudinally so as to be supported by the brackets 2 and 3. A hook or bracket 6' may be provided to engage the off-set suspension member 4, which is in a higher horizontal plane than the remainder of the structure, and gives a central support thereto.

An alternative method of applying the principles of my invention is illustrated in Fig. 2, in which a separate central supporting and spacing device, shown in enlarged form in Fig. 4, is used, and may consist of a tubular structure comprising the body portion 7 and the two downwardly turned and recurved ends 8' and 9'. The body portion 7 is provided with an opening 10 adapted to receive the upwardly turned portion of a screw hook 9 or other similar device. When so placed as shown in Fig. 2 the members 8' and 9' will be in position to receive the inner ends of the corresponding device of the outer members 6' and 5'. The tubular central portions should be made of such sizes of tubing as will correspond to the standard sizes of rods in use for this purpose. When the inner ends of such members or rods are slid within the hollow ends of the central supporting member and the other ends are received by the end brackets they will be fully and rigidly supported and provide means by which when the curtains or other draperies are suspended by rings thereon, such draperies may be made to overlap when closed as indicated by the dotted lines in Fig. 1.

As the outer members 5 and 6 of the support are at different distances from the heading board of the window casing it will be necessary, in order that the member further removed shall be parallel thereto, to have the corresponding bracket 3 longer than the bracket 2 which supports the other member. But this is not essential as the slight divergence will not readily be noticed.

The method of applying my invention last described affords a convenient means of commercial application. The tubular central devices can be made in quantity and carried in stock, leaving nothing further to be done than to cut the end members to suitable lengths from stock material. Standard

DRAPERY SUPPORTING ROD.

lengths can thus be carried to meet any demand and irregular or odd lengths can be used with great economy of material.

I claim:

5. 1. A drapery supporting rod having an intermediate member bent substantially into a loop providing a central portion and two oppositely extended arms, the central portion, when the rod is in position, lying in a horizontal plane above the arms and in a vertical plane substantially between the arms and arranged to be supported by a hook or projection from a casing, and a pair of rod sections, each having one end telescopically associated with one of said arms.
- 10 2. A drapery supporting rod having an intermediate member bent substantially into a loop providing a central portion and two oppositely extended arms, the central portion lying in a horizontal plane above the arms and the arms each lying in a different vertical plane when the rod is in position, said central portion being arranged to be supported by a hook or projection from a casing.
- 15 3. A drapery supporting rod having an intermediate member bent substantially into a loop providing a central portion and two oppositely extended arms, the central portion lying in a horizontal plane above the arms and the arms each lying in a different vertical plane when the rod is in position, said central portion being arranged to be supported by a hook or projection from a casing.
- 20 4. A sectional drapery supporting rod including an intermediate member bent substantially into a loop providing a central portion and two oppositely extended arms, the central portion lying in a horizontal plane above the arms and the arms each lying in a different vertical plane when the rod is in position, said central portion being arranged to be supported by a hook or projection from a casing.

- 25 5. A sectional drapery supporting rod including an intermediate member bent substantially into a loop providing a central portion and two oppositely extended arms, the central portion lying in a horizontal plane above the arms and the arms each lying in a different vertical plane when the rod is in position, said central portion being arranged to be supported by a hook or projection from a casing.

Washington, D. C."

portion and two oppositely extended arms, the central portion lying in a horizontal plane above the arms and the arms each lying in a different vertical plane when the rod is in position, said central portion being arranged to be supported by a hook or projection from a casing, and a pair of rod sections, each having one end telescopically associated with one of said arms.

4. An article of manufacture comprising an intermediate member for sectional drapery supporting rods bent substantially into a loop providing a central portion and two oppositely extended arms, the central portion lying in a horizontal plane above the arms and the arms each lying in a different vertical plane when the member is in position, said central portion being arranged to be supported by a hook or projection from a casing and said arms each being adapted to have one end of a rod section connected thereto.

In witness whereof, I have hereunto subscribed my name this 26th day of March 1917, at Chicago, Cook county, Illinois.

MAX KLAUSCH.
